UNITED STATES PATENT OFFICE.

JOHN P. WEIS, OF NYACK, NEW YORK, ASSIGNOR TO METROPOLITAN SEWING MACHINE COMPANY, OF NYACK, NEW YORK, A CORPORATION OF NEW YORK.

SEAM FOR SEWED ARTICLES.

No. 921,189.

Specification of Letters Patent.

Patented May 11, 1909.

Application filed July 7, 1905. Serial No. 268,653.

To all whom it may concern:

Be it known that I, JOHN P. WEIS, a citizen of the United States, residing in Nyack, county of Rockland, and State of New York, 5 have invented a new and useful Improvement in Seams for Sewed Articles, of which the following is a description.

This invention relates to seams for sewed articles, and has special reference to seams 10 which are made over the edge, or edges, of pieces of fabric.

Among the objects of this invention may be noted the following: to produce a seam for sewed articles containing a plurality of 15 threads forming an ornamental edging, selvage or finish for the work; to produce an edging for work composed of two needle or upper threads, and a single lower or locking-thread; and to provide a seam which 20 will be not only ornamental, but which will form a wearing edge for the work.

With the above objects in view, my invention consists in the features and combinations hereinafter described and claimed.

25 In the drawings: Figure 1 is a perspective view showing the top surface of the work, the latter consisting of two pieces of fabric superposed and having their edges overstitched in accordance with my invention; and Fig. 2 is a perspective view of the work of Fig. 1, but showing the bottom surface of the work.

Primarily, it should be understood that, 30 although this seam is illustrated in connection with two pieces of superposed fabric, it may be applied to a single piece of fabric for the purpose of giving to the latter a selvage or finished as well as ornamental edge, thus giving the same greater durability 40 and increasing the wear of its edge, especially if the fabric be loosely woven or knitted.

Referring to the drawings, 1 indicates the fabric, 2 indicates one of the top threads and 45 3 indicates the other of the top threads, while 4 indicates the locking-thread. The arrow 5 indicates the line of feed. The thread 2 is manipulated so as to form a single line of straight stitching on the top 0 surface of the work, the said thread being passed through the work from the top surface and formed into loops 2^a at the bottom surface thereof. The thread 3 is also passed through the work from the top surface forming the loops 3^a at the bottom surface of the

work; but on the top surface of the work said thread 3 is carried over into the path of the loops of the thread 2, so as to surround the loops 2^a at the point where the latter pass into the work at the top surface 60 thereof, the loops thus formed of thread 3 being indicated by 3^b, said loops being thus held by the straight line of stitching of the thread 2 on the top surface of the work, as clearly shown in Fig. 1. A loop 4^a of the 65 locking-thread 4, is passed through both the loops 2^a and 3^a of the respective threads 2 and 3, extends from the bottom surface over the edge of the work and surrounds the loops 3^a at the point where they pass 70 into the work at the top surface thereof, said locking-loops 4^a thus holding the said loops 2^a and 3^a closely united in pairs on the bottom surface of the work and being in turn held by the loops 3^a on the top surface 75 of the work, the said loop 4^a extending thus from the bottom surface of the work across the edge and a distance over the top surface thereof. By thus manipulating the locking-thread, a straight line of stitching 80 of said thread occurs on the bottom surface of the work and loops of said thread are laid in parallelism over the edge of the work.

From the above description it will be seen that on the bottom surface of the work a 85 straight line of stitching occurs which holds loops of the respective top threads in parallelism and a loop of one of said top threads grouped or paired with a loop of the other top thread, while on the top surface of the work a line of straight stitching occurs which holds loops of a top thread, which latter is given a zigzag form and in turn holds the loops of the lower thread. Obviously, the tension placed upon either 90 the top threads or the locking-thread will, in a measure, change the location of the several loops; that is to say, the loops of the top threads which are on the bottom surface of the work may be drawn, by tension on 100 the locking-thread, into such position as to be located midway between the two surfaces of the work, instead of at the bottom edge of the work, as shown in the figures, or the bights of said loops may be located at any 105 point between the point of penetration of thread 3 on the top surface of the work and the point where said loops emerge from the fabric on the bottom surface thereof, or the tension on the threads 2 and 3 may draw 110

the locking-thread 4 on the bottom surface of the work, substantially to the line of penetration of the loops 3⁴, or to a position between the points of penetration of the loops 5 of the threads 2 and 3, thus giving to the locking-thread on the bottom surface a zig-zag form.

Among the advantages of this seam may be noted the following: An artificial selvage 10 is produced on the edge of the work which will save the latter from wear and will give to the edge of the work a finished and ornate appearance; the edges of knit goods and other elastic fabrics can be prevented 15 from inordinately stretching, pulling out or raveling; and an ornamental finish for the edges of work is produced.

Having described my invention, what I claim and desire to secure by Letters Patent is:

1. A seam for sewed articles comprising the fabric and a plurality of threads, said seam being characterized by having a thread forming a straight line of stitching on the 25 top surface of the fabric, loops of a second thread lying on the top surface of the fabric and enchain with the thread of said line of stitching, and loops of a third thread extending over the edge of the fabric and 30 enchain with the loops of the second thread on the top surface of the fabric, and with loops of said first two mentioned threads below the top surface of the fabric.
2. A seam for sewed articles comprising 35 the fabric and a plurality of threads, said seam being characterized by having two threads enchain on the top surface of the work, one forming a line of straight stitching and the other laid in loops at an angle 40 to said stitching, and having on the bottom

surface of the work two independent sets of loops, the loops of one set being inclosed respectively by the strands of the loops of the other set, and both said sets of loops being joined to the top surface loops by other 45 loops extending across the edge of the fabric.

3. A seam for sewed articles comprising the fabric and a plurality of threads, said seam being characterized by having two independent sets of loops on the bottom surface of the fabric and a straight line of stitching on the top surface of the fabric, the loops of the respective sets on the bottom surface of the fabric being arranged in pairs and one of each pair inclosing the other, and said sets of loops being joined with the straight line of stitching on the top 50 surface of the fabric by two enchain loops which cover the edge and top surface of the fabric.

4. A seam for sewed articles comprising the fabric and a plurality of threads, said seam being characterized by having the loops of two independent threads passed through the work from one surface to the other, said 55 loops being joined in pairs and brought together at the same point on the fabric by the loop of a third thread passed therethrough and over the edge of the fabric, and a line of zigzag stitching joining the said 60 loops of the third thread and the loops of one of the said independent threads.

In testimony whereof I have hereunto signed my name in the presence of two subscribing witnesses.

JOHN P. WEIS.
